(57) **CLAIM**

The ornamental design for a roll up bag carrier, as shown and described.

DESCRIPTION

FIG. 1 is a front perspective view of the roll up bag carrier in the closed position, showing my new design;

FIG. 2 is a front elevation view of the roll up bag carrier in the closed position;

FIG. 3 is a back elevation view of the roll up bag carrier in the closed position;

FIG. 4 is a side elevation view of the roll up bag carrier in the closed position;

FIG. 5 is an opposite side elevation view of the roll up bag carrier in the closed position;

FIG. 6 is an end elevation view of the roll up bag carrier in the closed position;

FIG. 7 is an end elevation view of the roll up bag carrier in the open position;

FIG. 8 is a perspective view of the roll up bag carrier in use as a handle;

FIG. 9 is a front perspective view of the roll up bag carrier in use as a handle for carrying an unrolled bag, as shown; and,

FIG. 10 is a front perspective view of the roll up bag carrier with the bag shown in FIG. 9 rolled up and removably internested within the carrier for transporting the bag.

The broken lines in the drawings depict environmental subject matter only and form no part of the claimed design.
